DIE HOLDER FOR NAIL MAKING DIES

Ignacy Werner, Buffalo, N. Y.

Application August 25, 1938, Serial No. 226,667

7 Claims. (Cl. 10—49)

This invention relates to holders for nail making dies, and is particularly directed to die holders for regulator polygonal dies of the type disclosed in my Patent No. 2,115,544, issued April 5, 1938.

An object of this invention is to provide die holders of the character described having means for firmly and rigidly clamping the dies in operative position.

10 A further object of this invention is to provide strong and rugged die holders of the character described, which shall be relatively inexpensive to manufacture, easy to assemble and disassemble, and withal practical and efficient to a high degree.

15 Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

20 In the accompanying drawings, in which is shown one of the various possible illustrative embodiments of this invention,

Figure 1 is a top plan view of a pair of die holders embodying the invention, carrying regular pentagonal dies;

25 Figure 2 is a top plan view similar to Figure 1, but illustrating die holders embodying the invention for carrying regular octagonal dies;

Figure 3 is a top plan view of one of the die holders shown in Figure 1, with the bolts removed;

30 Figure 4 is an end view of the die holder shown in Figure 3;

Figure 5 is a top plan view of one of the die holders shown in Figure 1, with one of the clamping bolts in clamping position, and the other bolt 35 shown in position before insertion into the die holder;

Figure 6 is a top plan view of one of the die holders in Figure 2, with the bolts removed;

Figure 7 is an end view of the other die holder shown in Figure 2; and

Figure 8 is a top plan view of the other die holder shown in Figure 2, with one clamping bolt in clamping position, and the other bolt shown in position before insertion into the die holder.

50 Referring now in detail to the drawings, 10 and 11 designate a pair of complementary die holders embodying the invention. The die holder 10 is made of a block of steel and has downwardly and inwardly inclined front faces 12 and 13, top and

bottom parallel horizontal faces 14 and 15, and end faces 16 and 16a.

At the end face 16a, the die holder 10 has a cut away portion 17 of uniform horizontal cross-section forming parallel, inwardly facing similar surfaces 19, similar aligned shoulders 20, at right angles to surfaces 19, and symmetrical inclined faces 21, 21a. The die holder 10 is formed with a pair of similar parallel horizontal, longitudinal, symmetrically disposed through openings 22, communicating with the cut out 17. Each opening 22 forms a semi-circular opening in a shoulder 20 and a semi-cylindrical groove in a face 19. Disposed within the bolt openings 22 is a pair of similar symmetrical die clamping bolts 23 having screw threaded end portions 24 extending beyond the rear end 16 of the die holder 10, to receive nuts 26.

At the other end of each bolt 23 is a head 28 having a semi-cylindrical surface 29 contacting one of the surfaces 19, and a surface 30 disposed adjacent the shoulder 20. The top and bottom surfaces of the head 28 are flush with the top and bottom surfaces 15, 14 of the die holder 10. The inner surface 32 of the head 28 is inclined to the longitudinal axis of the die holder. The outer surfaces 33 of the heads 28 are aligned with the end surface 16a of the die holder.

Supported by the die holder 10 is a regular pentagonal die 35, such as shown in my Patent No. 2,115,544, issued April 26, 1938. Two sides of the die 35 contact the inclined surfaces 21, 21a of the die holder. Two sides of the die 35 contact the inclined surfaces 32 of the heads 28. Thus, one face of the die 35 is parallel to end face 16a and is exposed for use in making nails.

As shown in the drawings, the outer faces of the die 35 are formed with central vertical longitudinal semi-cylindrical grooves 36.

The die holder 11 is substantially similar to the die holder 10 and symmetrically disposed thereto, but may be shorter, and carries a complementary die 35.

The die holder 10 at the end surface 16 thereof may be formed with an opening 39 to receive a headed pin 40 formed with a semi-spherical socket 42, and which may be struck when mounting the die holder in a die block, not shown.

In Figures 2, 6, 7 and 8 there is shown a pair of similar, symmetrical die holders 10a and 11a, similar to the die holders 10 and 11, except that the recesses or cut-outs 17a in the dies, and the heads 28a of the bolts are designed for holding regular octagonal dies 35a instead of regular pentagonal dies, as shown in Figure 1.

The die holders 10a and 11a thus have cut outs 11a to contact five sides of the die 35a, and the bolts 23a have heads 28a to contact two other sides of the die. Thus, each die holder carries a die with one exposed face.

5 It will be understood that a pair of die holders supports a pair of multi-faced, complementary, similar symmetrically mounted dies which may be adjusted to bring different pairs of grooves 36 into working position, as the grooves wear out. When 10 a pair of grooves wears out, the nuts 26 are unscrewed, the bolts are taken out, the dies are rotated to bring differential sets of grooves into operative position, the bolts are then reinserted in 15 the die holders the nuts are again screwed to the bolts and tightened to hold the dies in the die holders in their new positions.

It will thus be seen that there is provided a device in which the several objects of this invention are achieved, and which is well adapted to meet the conditions of practical use.

20 As various possible embodiments might be made of the above invention, and as various changes might be made in the embodiment above 25 set forth, it is to be understood that all matter herein set forth or shown in the accompanying drawings is to be interpreted as illustrative and not in a limiting sense.

Having thus described my invention, I claim as 30 new and desire to secure by Letters Patent:

35 1. A die holder having a cut out at one end formed with a pair of parallel vertical inner faces, and a pair of vertical faces inclined to one another, said die holder being formed with a pair of parallel through openings communicating with opposite ends of said cut out, said bolts having heads at one end within said cut outs contacting the parallel faces of said cut out, said heads being formed with vertical inclined faces cooperating 40 with the first mentioned vertical inclined faces to support a polygonal die.

45 2. A die holder comprising a member having a cut out at one end, of uniform horizontal cross-section, extending from the top to the bottom surface of said holder and forming a pair of parallel, vertical, similar inner faces, a pair of aligned, symmetrically disposed shoulders, and a pair of symmetrically disposed faces inclined to one another, said member being formed with a pair of similar, symmetrically disposed, horizontal 50 through openings communicating with the end of said cut out, bolts in said through openings having heads within said cut out, said heads having inclined faces whereby a polygonal die may be received in said cut out between said member and the heads of said bolts.

55 3. A die holder comprising a member having a cut out at one end, of uniform horizontal cross-section, extending from the top to the bottom surface of said holder and forming a pair of parallel, vertical, similar inner faces, a pair of aligned, symmetrically disposed shoulders, and a pair of symmetrically disposed faces inclined to one another, said member being formed with a pair of similar, symmetrically disposed, horizontal 60 through openings communicating with the end of said cut out, bolts in said through openings having heads within said cut out, said heads having inclined faces whereby a polygonal die may be received in said cut out between said member and the heads of said bolts, said die holder being formed, at the opposite end thereof, with an opening, and a headed pin having a shank received in said opening, the head of said pin being formed with a semi-spherical socket.

4. A pair of die holders having cut outs at adjacent ends, and pairs of parallel through openings communicating with said cut outs, pairs of bolts in said pairs of through openings, having spaced heads within said cut outs, and similar dies of regular polygonal cross-section within said cut outs and held therein by the heads of said bolts, and having exposed faces between said heads, the faces of said dies having central grooves of semi-cylindrical cross-section.

5 5. A die holder comprising a member having parallel vertical end surfaces, and parallel horizontal top and bottom surfaces, said member having a cut out at one end surface, of uniform horizontal cross section, extending from the top 10 surface to the bottom surface, said cut out having a pair of parallel, vertical inner surfaces, extending from the adjacent end surface, at right angles thereto, and with similar, aligned vertical surfaces extending from said inner surfaces, at 15 right angles thereto, and with vertical, inclined surfaces, between said aligned surfaces, said member being further formed with a pair of horizontal, longitudinal, similar, symmetrically disposed through openings communicating with the 20 end of said cut out and forming semi-circular openings in said aligned surfaces, and horizontal semi-cylindrical grooves in said inner surfaces, a pair of similar, symmetrically disposed die 25 clamping bolts in said through openings having heads at one end within said cut out, said heads having top and bottom surfaces flush with the top and bottom surfaces of said member, and with outer faces flush with said adjacent end surface of said member, with surfaces parallel to 30 said outer faces and disposed adjacent said aligned surfaces, and with inner inclined surfaces.

6. A die holder comprising a member having parallel vertical end surfaces, and parallel horizontal top and bottom surfaces, said member having a cut out at one end surface, of uniform horizontal cross section, extending from the top 40 surface to the bottom surface, said cut out having a pair of parallel, vertical inner surfaces, extending from the adjacent end surface, at right angles thereto, and with similar, aligned vertical surfaces extending from said inner surfaces, at right angles thereto, and with vertical, inclined surfaces between said aligned surfaces, 45 said member being further formed with a pair of horizontal, longitudinal, similar, symmetrically disposed through openings communicating with the end of said cut out and forming semi-circular openings in said aligned surfaces, and horizontal semi-cylindrical grooves in said inner surfaces, 50 a pair of similar, symmetrically disposed die clamping bolts in said through openings having heads at one end within said cut out, said heads having top and bottom surfaces flush with the top and bottom surfaces of said member, and with outer faces flush with said adjacent end surface of said member, with surfaces parallel to 55 said outer faces and disposed adjacent said aligned surfaces and with inner inclined surfaces, and a die of regular polygonal horizontal cross section within said cut out and between the inclined surfaces of said member and the inclined surfaces of the heads of said bolts, and having an exposed face disposed between said heads and 60 parallel to said adjacent end surface of said die holder.

7. A die holder comprising a member having parallel vertical end surfaces, and parallel horizontal top and bottom surfaces, said member 75

having a cut out at one end surface, of uniform horizontal cross section, extending from the top surface to the bottom surface, said cut out having a pair of parallel, vertical inner surfaces, extending from the adjacent end surface, at right angles thereto, and with similar, aligned vertical surfaces extending from said inner surfaces, at right angles thereto, and with vertical, inclined surfaces between said aligned surfaces, said member being further formed with a pair of horizontal, longitudinal, similar, symmetrically disposed through openings communicating with the end of said cut out and forming semi-circular openings in said aligned surfaces, and horizontal semi-cylindrical grooves in said inner surfaces, a pair of similar, symmetrically disposed die clamping bolts in said through openings having heads at

one end within said cut out, said heads having top and bottom surfaces flush with the top and bottom surfaces of said member, and with outer faces flush with said adjacent end surface of said member, with surfaces parallel to said outer faces and disposed adjacent said aligned surfaces, and with inner inclined surfaces, and a die of regular polygonal horizontal cross section within said cut out and between the inclined surfaces of said member and the inclined surfaces of the heads of said bolts, and having an exposed face disposed between said heads and parallel to said adjacent end surface of said die holder, the other end of said member having an opening and a pin in said last mentioned opening having a head formed with a socket.

IGNACY WERNER.
